UNITED STATES PATENT OFFICE.

ARTHUR L. ALLIN, OF MIDDLETOWN, CONNECTICUT.

DESIGN FOR A BICYCLE FOOT-REST.

SPECIFICATION forming part of Design No. 26,947, dated April 20, 1897.

Application filed January 4, 1897. Serial No. 619,122. Term of patent 7 years.

To all whom it may concern:

Be it known that I, ARTHUR L. ALLIN, a citizen of the United States of America, residing at Middletown, in the county of Middlesex and State of Connecticut, have invented and produced a new and original Design for Bicycle-Plates for Foot-Rests, of which the following is a description, reference being had to the accompanying drawings, wherein—

Figure 1 is a flatwise view of a bicycle-plate for foot-rests embodying said design. Fig. 2 is a view of the same in vertical cross-section on the plane denoted by the dotted line xx .

The essential feature of the design is that of a regularly-tapered serrated outline upon both the upper and lower edges of a bicycle-plate for foot-rests. 15

I claim—

The design for a bicycle-plate for foot-rests substantially as shown and described.

ARTHUR L. ALLIN.
